UNITED STATES PATENT OFFICE

HORACE L. SMITH, JR., OF RICHMOND, VIRGINIA, ASSIGNOR, BY MESNE ASSIGNMENTS, TO AUTO RAMPS CORPORATION, OF RICHMOND, VIRGINIA, A CORPORATION OF VIRGINIA

GARAGE-RAMP SYSTEM

Application filed November 30, 1926. Serial No. 151,754.

This invention relates to an improved garage ramp system, and aims to provide a simple, practical and economical arrangement for storing motor vehicles on a considerable scale, particularly in cities where ground space is expensive and difficult to obtain.

One of the objects of the invention is to provide a multi-story garage having a ramp unit so constructed and arranged that ascending and descending automobiles may be driven through, into and out of the ramps without interfering with each other, and a maximum number of automobiles may be driven through the system within a given time.

Other objects and advantages of the invention will be more fully explained in the following detailed description, which is to be read in connection with the accompanying drawings illustrating several ways in which the invention may be embodied.

In the drawings:

Figure 1 is a view, partly in elevation and partly in section, of a building constructed according to the invention.

Figure 2 is a vertical sectional view showing the ramps and the adjacent walls.

Figure 3 is a horizontal section through the building.

Figure 4 is a plan view of the ramps and adjacent walls.

Figure 5 is a vertical section through the upper part of the ramps, showing a modified form thereof.

Figure 6 is a horizontal section through the ramps and adjacent walls showing another modification.

Referring to the drawings, and particularly to the embodiment of the invention shown in Figures 1 to 4, my improved ramp system is constructed as a unit in and forms a part of a garage building 10, made of suitable material such as reinforced concrete, and having a number of storage floors 11. The ground floor preferably has a number of doorways 12, appropriate ones of which may be designated "Enter" and "Exit" to avoid interference between incoming and outgoing traffic.

As best shown in Figures 2 and 3, the illustrative ramp system is located approximately

in the center of the building, and is formed, in this instance, by providing spaced cylindrical or substantially cylindrical curtain and supporting walls 13 and 14 extending from the ground floor to the roof of the building, the inner wall providing a storage space known as the core and adapted to be used for various purposes, such as for washing and greasing service, as well as for parking space.

Between the walls 13 and 14, there is shown a pair of ramps or driveways 15 of the double-screw or helical type, one for ascending traffic and the other for descending traffic, and the pitch being the height of two floors. That is to say, the arrangement is such that an automobile on driving one round will ascend or descend two stories. This enables traffic to move rapidly.

Each of the ramps or driveways, where it intersects a floor, has a flat landing portion 17 forming a continuation of each floor and aligned openings 18 are provided in the walls 13 and 14 to permit automobiles to enter them. Further, the floors in the core portion of the ramps are a part of the floors of the building. The openings are so arranged that an automobile may be driven from any main floor directly into the core portion for service. Moreover, the openings are substantially 80 diametrically arranged.

Since my ramps have a pitch of two stories, exit doors for the ascending ramp and entrance doors for the descending ramp will be arranged one above the other on opposite sides. That is the door on the second floor above the ascending ramp door leads to the descending ramp, and the doors for the ascending ramp and the descending ramp on any floor will be on opposite sides of the ramp structure or unit. This arrangement enables motorists to avoid traffic going in the opposite direction on the floor. In fact, the open driveways on the floors may be so arranged that, at no time, will a departing motorist cross the path of one who is parking.

To provide for daylight in the core of my ramp unit, I have shown windows 20 and 21 in the walls 13 and 14, respectively. Herein, there are two such windows substantially di-

metrically opposite each other in each wall.

If the ramps terminate at the upper floor 11, a safety railing 22 is built around the same. If desired, however, the ramps may be continued through the roof 23 as shown in Figure 5, and a pent house 24 may be built over the same. It may also be desired to bank the ramps, as indicated at 15^a and 16^a in Figure 5.

10 Instead of building the walls 13 and 14 cylindrical, it may be preferred to build them with many sides tangential to a cylinder, as indicated at 13^b and 14^b in Figure 6. In order to minimize the fire hazard, it may also be preferred to provide fire doors 25 at each floor, as shown in Figure 6. These doors may be of any type approved by the underwriters. As soon as the doors are closed fire and smoke is prevented from spreading from 20 one floor to another because the sections of each ramp between the floors will be closed.

In the operation of my system, a continuous stream of ascending traffic may enter the ascending ramp on the ground floor while an 25 independent stream of traffic is passing out of the descending ramp exit on the opposite side. The ascending automobiles climb continuously on a uniform curve and grade until they reach the respective parking floors. 30 This enables the motorist to set his steering wheel upon entering a ramp, and then complete the journey without changing it, thus avoiding the necessity to make right-angle turns. They do not cross the path of the exit traffic either in the ramp system or on the floors. Thus, my arrangement not only enables traffic to move at a maximum speed, but avoids danger of accidents. Using ramps wide enough for only one automobile, the 35 capacity of my system is about one thousand automobiles per hour. Moreover, the ramp is very compact, thereby conserving very valuable floor space and, at the same time, has a maximum car capacity. The transverse dimension is determined with reference to the 40 minimum circle in which an automobile can negotiate continuously.

From the foregoing description, it is clear that my improved system constitutes a very 45 important advance in the solution of the parking problem in congested areas.

Obviously, my invention is not limited to the particular embodiments thereof herein shown and described.

55 In certain of the subjoined claims the radius of the spiral driveways is defined in terms of the turning radius of the cars which the building is designed to house. For the present-day automobile this means a radius 60 for the inner curve of the ramp of approximately 20 feet and a radius for the outer curve of approximately 32 feet, thereby providing a 12-foot drive which allows an ample factor of safety for passenger vehicles of 65 the larger size. The claims are not to be un-

derstood as limited to these dimensions, as they may be decreased for cars of smaller turning radius, with the advantage of providing additional floor storage space, or increased for garages designed for larger vehicles, for example, omnibuses and the like. The ramp of the present application is adaptable for either large or small cars with the minimum loss of storage space. A small, light car can ascend a steeper grade than a 75 large heavy vehicle. A circular spiral ramp along which the cars travel with their steering gears turned to approximately their greatest extent, obviously affords the shortest path of travel from one point to another, and by superimposing the up and down ramps in the manner described, two complete separate driveways are provided in the minimum space possible for the movement of the cars.

The expressions "just greater" and "just less" as used in the appended claims are intended to define ramp dimensions sufficiently greater and smaller, respectively, than the automobile turning radius, to provide a driveway of ample width.

What is claimed is:

1. In a garage building superimposed horizontal storage floors spaced to provide full head room between the successive floors, a ramp structure providing separate automobile driveways for ingress to and egress from the successive floors of the building, said ramp structure comprising two superimposed substantially continuous helical driveways having a common vertical axis, the outer radius of said driveways being just greater than the turning radius of greatest amplitude of the cars the building is designed to accommodate, the inner radius of said ramps being just less than said turning radius, and the middle lines of said driveways being throughout the length of the driveways at the same distance from the vertical axis, said distance being such that automobiles can traverse the length of the ramp without change in the position of their steering wheels.

2. In a garage building, superimposed horizontal storage floors spaced to provide full head room between the successive floors, a ramp structure providing separate automobile driveways for ingress to and egress from the successive floors of said garage, said ramp structure comprising two superimposed substantially continuous helical driveways having a common vertical axis, the outer radius of said driveways being just greater than the turning radius of greatest amplitude of the cars the garage is designed to house, the inner radius of said ramps being just less than said turning radius, and the middle lines of said driveways being throughout the length of the driveways at the same distance from said vertical axis whereby cars can traverse the length of the ramp without change in the position of the steering wheels, and the pitch of

said spirals being such that the ramps intersect the floor levels at each half turn of the spiral.

3. In a garage building, superimposed horizontal storage floors spaced to provide full head room between the successive floors, a ramp structure providing separate automobile driveways for ingress to and egress from the successive floors of said garage, said ramp structure comprising two superimposed substantially continuous helical driveways having a common vertical axis and a pitch such that the ramps intersect the floor levels at each half turn, floors at substantially the levels of the storage floors extending transversely across the space within the inner radius of said helices, the outer radius of said driveways being just greater than the turning radius of greatest amplitude of the cars the garage is designed to house, the inner radius of said ramps being just less than said turning radius, and the middle lines of said driveways being throughout the length of the driveways at the same distance from said vertical axis whereby cars can traverse the length of the ramp without change in the position of the steering wheels.

In testimony that I claim the foregoing as my own I have hereto affixed my signature.
